UNITED STATES PATENT OFFICE.

CHARLES BURROWS, OF SCHENECTADY, NEW YORK.

RULING-MACHINE.

SPECIFICATION forming part of Letters Patent No. 619,717, dated February 21, 1899.

Application filed September 2, 1896. Serial No. 604,607. (No model.)

To all whom it may concern:

Be it known that I, CHARLES BURROWS, a citizen of the United States, and a resident of Schenectady, in the county of Schenectady, 5 and State of New York, have invented certain new and useful Improvements in Ruling-Machines, of which the following is a specification.

My invention relates to improvements in machines for ruling flat paper, and relates more particularly to improvements on my invention set forth and described in Letters Patent No. 568,236, issued to me and dated September 22, 1896, for ruling-machines; and it 15 consists in the combinations of devices and elements hereinafter described, and set forth in the claims.

The object of my invention is to provide a positive means by which the pen-beam may 20 be nicely adjusted in direction transversely to that of the direction the carrying-apron of the machine is run and then be secured from being accidentally moved longitudinally in either direction. I attain this object by the 25 means illustrated in the accompanying drawings, forming a part of this specification, in which—

Figure 1 is an elevation illustrating my invention, and Fig. 2 is a front elevation with 30 a part shown in section.

The same letters of reference refer to similar parts throughout both views.

In the drawings, A is a portion of the framework of the ruling-machine, and B is the end-less apron.

C is the pen-beam, and E is an adjustable standard (one of the two) for supporting the adjustable bearing G of the end pintle of the pen-beam C. The said adjustable standard 40 and means for adjusting the said bearing G are fully described in my above-mentioned Letters Patent No. 568,236. I will therefore only briefly refer to the principal parts of the same, so as to connect the improvements in 45 this invention with the parts employed in my former invention.

The standard E, by its smooth-bore sleeves b b', holds in place the horizontal sleeve F, which is integral with and mounted on the 50 screw-threaded vertical post F' and calculated to be elevated or lowered accordingly as the revolving finger-nut F³ is revolved.

The adjustable bearing G has its arm G' contained in the horizontal sleeve F and is held in place adjusted to by means of the split 55 sleeve portion, provided with lugs and the clamping bolt or screw F².

The end pintle C' of the pen-beam C is preferably made and secured with the ends of said pen-beam (but one shown) in the 60 manner generally practiced by the trade. In the drawings the pintle C' is shown to have its inner end portion provided with a journal c, of less diameter than the body of said pintle, working in sleeve C², having with it the 65 flange-collar c' and screw end c², screwing into the end of the pen-beam C. This journal c of said pintle is shown to be held from moving longitudinally by means of nut c³ and jam-nut c⁴, screwing on the screw-threaded 70 stem portion of said pintle-journal, as shown. This end pintle C' is provided with a finger-head C⁵ for convenience of revolving it at will in either direction, and it has between the sleeve C² and finger-head C⁵ a screw-thread C⁴. The bearing G of this end pintle 75 C' of the pen-beam has heretofore been in the form of an annular wall unbroken in its continuity and having in its bore a screw-thread corresponding with the screw-thread C⁴, provided on the pintle C'. These plain screw-threaded bearings, with their unbroken walls, by use become worn, as do the screw-threads C⁴ of the pintle, and allow a gradual though slow change of the place of the pintle in its bearing, 80 and thereby effect an endwise movement of the pen-beam, which gradually becomes so great as to cause the points of the pens to strike the paper carried by the apron at a greater or less distance from the points originally had 85 and intended to be preserved in all the sheets ruled. This change is a serious defect which my present invention is intended to remedy.

In this invention the pintle-bearing G is slit from one side thereof, and preferably from 90 its lower side, and this bifurcated wall has integral with it the lugs g g', one of which, as g, is perforated with a plain hole, and the other, as g', is provided with a screw-threaded 95 perforation.

A clamping-screw G², passing 100 through the plain perforation in lug g and having its screw-threaded stem working in the screw-threaded perforation of lug g', serves as a means for contracting the diameter of the

wall of the bearing G when the said clamping-screw G² is turned in a proper direction for drawing the lugs g g' toward each other. This split pintle-bearing is provided with an 5 internal screw-thread S, which corresponds with the screw-thread C⁴, provided on the pintle C', so as to nicely work in the same when the latter is revolved by its finger-head C³ in either direction. When this pintle C' 10 is revolved in one direction, the coacting screw-threads C⁴ and S will operate to move the pen-beam longitudinally away from the said bearing G, while when revolved in the opposite direction they operate to carry the 15 said pen-beam longitudinally toward said bearing G, and by such movements as may be necessary to be made an operator may readily adjust the pen-beam in either direction, and thereby carry the point or points of 20 the pens to particular points on the paper to be ruled and carried by the apron beneath the pens. When the pen-beam has been adjusted ready for working the machine, the operator will tighten the clamping-screw so 25 as to draw the lugs g g' toward each other. The split walls of the said bearing will be tightened on the screw-thread portion of the pintle and held so tight on the same as to prevent a relative movement of the pintle 30 and its bearing with each other, and thereby cause all movements between the pintle and the pen-beam to occur at the joint between the journal c of the pintle and the sleeve C², and thereby positively prevent the pen-beam 35 shifting in either direction in relation to the apron carrying the sheets of paper beneath the pens and in direction transversely to the direction of length of said pen-beam, and also prevent any vibration or shake of the said 40 pen-beam when the screw-thread on the pintle becomes loose by wear.

Having described my invention, what I claim, and desire to secure by Letters Patent, is—

45 1. In a ruling-machine the combination

with a pen-beam, a pen-beam pintle C' provided with the screw-thread C⁴ and journal c of less diameter than that of its screw-threaded body and having its outer end portion screw-threaded and provided with nuts c³ and c⁴, a 50 sleeve C² receiving the said journal portion of the pintle and provided with flange c' and the screw-threaded end portion c² screwing into the end of the pen-beam, of the internal screw-threaded pintle-bearing G having a 55 split wall and lugs g g' each perforated and one having its perforation screw-threaded, and the clamping set-screw G², whereby said pen-beam may be longitudinally adjusted in either direction, at will, and be secured from 60 shifting with permission for free vertical oscillation substantially as and for the purposes set forth.

2. In a ruling-machine the combination with vertical standard E provided with sleeves 65 b b', vertical post F working in said sleeves and provided with screw-threads and integral with the horizontal sleeve F having a split side wall and a screwing device for contracting said wall at will, of the screw-threaded 70 bearing G having a split wall and a screw clamping device for contracting said split wall, at will, and made integral with arm G' which is adjustably secured within the split wall of the said horizontal sleeve, a pen-beam, 75 sleeve C² screwed into the end of said pen-beam, pintle C', having journal c of smaller diameter than its body and provided on its larger portion with screw-threads C⁴, which are received in the screw-threaded bearing G 80 and having the finger-head C³, whereby said pen-beam may at will be both longitudinally and vertically adjusted and secured as set, with permission for free vertical oscillation, 85 substantially as and for the purposes set forth.

CHARLES BURROWS.
